UNITED STATES PATENT OFFICE

GUSTAVUS H. BOEHMER, OF ST. LOUIS, MISSOURI

SHOE

Application filed February 15, 1928. Serial No. 254,365.

This invention relates to footwear and has for an object thereof the provision of a shoe the forepart of which, during use, will flex along a line that coincides with a natural hinge that exists in the bone structure of the foot.

It is perfectly obvious that as the weight of a person is shifted from the heel to the toe of the foot in walking, that the foot bends along a line extending transversely to the length-wise dimension of the foot; this line marking the junction between the five phalanges and the five metatarsal bones of the foot. Heretofore it has been customary to provide shoes having the forepart of the shoe bottom uniformly flexible throughout its entire length, and it is only through continual wearing of the shoe that a line of bend most natural to the foot becomes established. Thus, in the beginning the stiff shoe bottom, being reluctant to bend, tires and weakens the foot, and later, when the shoe bottom has assumed a line of bend the shoe is badly worn. Furthermore, the gradual wearing down of the sole produces a bending area in the region located beneath the junction between the metatarsals and the phalanges, instead of a line of bend, and consequently the sole does not flex along a definite line, but arches with the crown of the arch located somewhere within the bending area. Accordingly, as hereinbefore mentioned, the present invention aims to obviate this objectionable feature by providing a shoe, the bottom of which is formed with a definite line along which the shoe bottom bends upon being flexed. This line is positioned in a predetermined relation to the junction between the metatarsals and the phalanges whereby the shoe bottom forms a natural hinge for the bones of the forepart of the foot.

A feature of the invention which aims towards the accomplishment of the recited object consists in constructing a shoe bottom in such a manner that it will flex most readily along a line extending transversely of the lengthwise dimension of the bottom approximately beneath the junction of the metatarsal and phalanx bones of a foot mounted within the shoe. In the illustrated embodiment

of the invention this feature has been accomplished by molding the shoe bottom parts in such a manner that when assembled the molded parts will occupy a close fitting relationship to each other, and lines definitely molded in all of the parts will coincide vertically with one another in providing a line of flex of the assembled shoe bottom.

Inasmuch as a shoe bottom of the improved type provides an important support for the bottom of the foot; tends to prevent weakening or tiring of the forepart of the foot brought about by unnatural bending; and serves to support gently and properly an already weakened arch, an important feature of the invention consists in the provision of a health shoe having a raised center arch for fitting snugly up under all parts of the foot, and a molded line of flex located at the forward end of the raised central arch for acting as a hinge during the use of a shoe. Such a provision supports properly the bones of the foot and also insures that in the use of the shoe the bones will bend in a natural and intended manner.

Other features and objects of the invention will become apparent from a reading of the specification in the light of the accompanying drawings, in which:

Fig. 1 is a view in side elevation having certain parts broken away to show the construction of the shank of the shoe.

Fig. 2 is a bottom of a shoe having certain parts broken away more clearly to show the construction of the shank.

Fig. 3 is a view in perspective of an insole employed in the shoe.

Fig. 4 is a diagrammatic view showing the position of the bones of the foot with relation to the bottom of the shoe.

Fig. 5 is a view in perspective showing the outer sole of the shoe.

Fig. 6 is a cross-sectional view of the shoe taken along the line 6-6 of Fig. 1, and

Fig. 7 is a view in perspective of a wedge piece with which the shoe is provided.

As shown in Fig. 4 of the drawings, the forepart of a human foot is comprised, mainly, of five metatarsal bones M and five phalanges P which are joined together to form

a hinge-like structure permitting the bending of the foot. As hereinbefore pointed out, an object of the invention is to provide an improved shoe having a bottom which will flex 5 readily along the line located approximately directly beneath the junction between the metatarsals and the phalanges, and accordingly an out-sole 10 is molded to form a sharp break, or line of bending 12 which extends 10 transversely of the lengthwise dimension of the shoe as shown more clearly in Figs. 4 and 5.

This line 12 is located approximately in vertical alinement with the junction of the 15 metatarsals and phalanges of a person wearing the shoe, or if not in vertical alinement, then in such a position relatively to the junctions that the shoe bottom supports the foot and permits it to be bent in the most natural 20 manner. As shown in Fig. 4, the line is located slightly in the rear of the junction and is curved to simulate the curvature of a line drawn through the five junctions of the fore-part bones.

25 Inasmuch as it is desirable that all of the bottom parts of the shoe be so constructed as to permit the forepart of the shoe to bend readily along the line 12 upon being flexed, the various parts of the shoe bottom are molded 30 similarly to the manner in which the out-sole is molded. Such a provision permits the parts of the shoe bottom to be assembled, as shown in Fig. 1, with a line of bending formed in each of the bottom parts, these parts being 35 so assembled that the lines of bending are in vertical alinement. Thus an insole 14 may be molded to form a sharp break 16, as shown in Fig. 3. Also, since a metal shank stiffener or arch support which extended between the 40 out-sole and the insole and spanned the line of break in those parts would interfere with the bending action of the shoe bottom along the line of break, there is provided a shank piece 18 the forward end of which terminates 45 in the rear of the lines 12 and 16. A wedge piece 20 of leather, fiber board or other suitable material is interposed between the forward edge of the shank piece 18 and the out-sole 10 to prevent the metal piece from 50 injuring the out-sole and this wedge piece is likewise molded along the line 22 to render the piece freely resilient along that line in order that it will bend in unison and harmony with the other parts of the shoe bottom.

55 Thus it will be seen that the entire shoe bottom is so constructed that upon being flexed (as shown by dotted lines in Fig. 1) the forepart will bend along the break that is molded in the shoe parts of the bottom. It is 60 to be expressly understood that while this feature is carried out in the illustrated embodiment of the invention by means of molding the bottom parts, the invention contemplates forming them in any suitable manner 65 so long as there will be established a definite

line along which the shoe bottom will bend upon being flexed. This might be done by making the shoe parts relatively thin along the line in question, or grooving the parts along this line, by cutting a gash in them 70 along the line, etc., or forming the insole in two parts.

In the construction of a shoe embodying the invention the wedge piece may be secured to the shank piece in any suitable manner, 75 as, for example, by riveting, cementing, etc.

As already pointed out the invention is adaptable to health shoes inasmuch as it permits the foot and the shoe to bend easily in the most natural manner. Accordingly the 80 drawings illustrate a shoe, the central arch portion of which is raised as shown at 23 (Fig. 6) whereby the foot is so supported that the bone structure is neither crowded together nor collapsed. To further carry out 85 the idea of firmly supporting the arch so that all parts of the foot are in snug engagement with the bottom of the shoe, the shank piece 18 is curved both longitudinally and transversely and the outer-sole of the shoe is 90 arched transversely as shown at 24. A shoe of this type, having its shank arched both longitudinally and transversely, can be built on a last such for example as that disclosed in my United States Letters Patent No. 95 1,575,527, granted March 2, 1926.

Thus it will be seen that the shoe is constructed in a way that best supports the bones of the foot and also in such a manner that in walking the bones bend naturally and this 100 bending is not opposed by the stiffness of the shoe bottom as occurs in shoes today, but is assisted by means of the breaks that are molded in the bottom parts.

It is to be understood, of course, that the 105 invention may be embodied with equal facilities in shoes of all styles, for example, Good-year welts, McKays, turns, stitch-downs, etc. Furthermore, it is to be distinctly understood that the term "line" as herein used is not restricted to a knife-edge line but includes likewise an area resembling a narrow strip when that area is rendered resilient or easily flexible during the manufacture of a shoe, for the purpose of providing the shoe bottom 110 115 with a hinge.

Having thus described my invention what I claim as new and desire to secure by Letters Patent of the United States is:

1. A shoe comprising, in combination, an 120 upper, and a bottom secured to the upper, all of the parts of the bottom being formed with breaks located in vertical alinement with one another approximately directly beneath the junction between the metatarsal and phalangeal bones of a foot mounted within the shoe, said breaks being in the form of curved lines extended transversely of the shoe 125 from one side thereof to the other.

2. A shoe comprising, in combination, an 130

upper, an outsole, and an insole arranged above the outsole, the outsole and the insole being provided with vertically coincident lines of break located approximately directly beneath the joints between the metatarsal and phalangeal bones of a foot mounted within the shoe, said lines of break being in the form of curved lines extended transversely of the shoe from one side thereof to the other.

3. A shoe comprising, in combination, an upper, an outsole, and an insole arranged above the outsole, the outsole and the insole being provided with vertically coincident molded lines of break located approximately directly beneath the joints between the metatarsal and phalangeal bones of a foot mounted within the shoe, said lines of break being in the form of curved lines extended transversely of the shoe from one side thereof to the other.

4. A shoe comprising, in combination, an upper, an outsole secured to the upper, an insole arranged above the outsole, the outsole and the insole being formed with vertically coincident lines of break, and a shank stiffener disposed between the outsole and the insole, the forward edge of the shank stiffener terminating in the rear of the lines of break in the outsole and the insole, said lines of break being in the form of curved lines extended transversely of the shoe from one side thereof to the other.

5. A shoe comprising, in combination, an upper, an outsole having a molded line of break extending approximately directly beneath the joints of the metatarsal and phalangeal bones of a foot mounted within the shoe, an insole, a shank stiffener interposed between the insole and the outsole, the forward edge of the shank stiffener terminating in the rear of the line of break in the outsole, and a member positioned at the forward edge of the shank stiffener to protect the outsole from injury by the forward edge of said shank stiffener, said insole and said member each having a molded line of break which coincides with the line of break of the outsole.

In testimony that I claim the foregoing I hereunto affix my signature.

GUSTAVUS H. BOEHMER.
